WILLIAM B. ELLIS, OF ATLANTA, GEORGIA

CHARGE-FORMING DEVICE

Application filed April 9, 1928. Serial No. 268,765.

This invention relates to charge forming devices designed primarily for use in connection with internal combustion engines, but it is to be understood that a charge forming device in accordance with this invention may be employed for any purposes wherein it is found applicable, and the invention has for its object to provide, in a manner as hereinafter set forth, for the conversion of liquid fuel into a gas or vapor state prior to the mixing thereof with air and to increase the temperature of the mixed charge prior to its entry into the explosion chamber of the engine.

Another object of the invention is to provide, in a manner as hereinafter set forth, a heating unit for utilizing the temperature of the products of combustion of an internal combustion engine to convert a liquid fuel into a gaseous or vapor state, and to further provide a conducting means therefor that insures a balanced continuous flow of said products around the parts to be heated by the unit.

Another object of the invention is to provide, in a manner as hereinafter set forth for a more perfect mixture of the explosive charge, less weight of fuel per cubic foot of mixture, a more perfect mixture at a lower temperature and therefore allowing a greater weight of explosive mixture per cubic foot of piston displacement, which in turn results in a higher compression pressure followed by an increased power stroke.

Further objects of the invention are to provide, in a manner as hereinafter set forth a charge forming device which is simple in its construction and operation, strong, compact and durable, thoroughly efficient in its intended purposes and inexpensive to manufacture.

With the foregoing and other objects in view the invention consists of the novel construction, combination and arrangement of parts as hereinafter more specifically described and illustrated, wherein is shown an embodiment of the invention, but it is to be understood that changes, variations and modifications may be resorted to which fall within the scope of the invention as claimed.

In the drawings wherein like reference characters denote corresponding parts throughout the several views:-

Figure 1 is a side elevation of an internal combustion engine showing the adaptation therewith of a charge forming device in accordance with this invention, the device being partly in section.

Figure 2 is a section on line 2-2 of Figure 1.

Figure 3 is a section on line 3-3 of Figure 1.

Figure 4 is a fragmentary view in longitudinal section of the device.

In the drawings 4 indicates an internal combustion engine, having an intake manifold 5, a supply pipe 5' opening thereinto of any suitable length, an exhaust manifold 6 opening into a discharge pipe 6', and a liquid fuel supply pipe 7 leading from a storage tank not shown in the drawing.

The heating unit in accordance with this invention comprises a pipe section 8 of a diameter in conformity with the diameter of and leading to the standard supply pipe 5'. The length of the pipe section 8 may be as desired depending upon the distance between the carbureting chamber and the supply pipe 5'. The ends of the pipe section 8 are preferably provided with flange couplings 9, 9' for connecting it between the casting designated generally at 10 and the pipe 5'. If desired the supply pipe 5' may be dispensed with and the pipe 8 connected directly to the intake of the manifold 5.

Intermediate the ends of the pipe section 8, extending concentrically thereof, and preferably made integral with its walls, is a closed substantially cylindrical shaped heating jacket 11. The jacket comprises a circular outer wall 12 spaced with respect to the pipe wall to form a heating space 13 therebetween, and including a closed top and bottom wall 14, 14'. Communicating with the heating space 13 and preferably made integral with the jacket wall 12 near the top thereof is a radially disposed tubular projection 15 which is adapted for connection with an opening 16 made in the exhaust manifold 6 for the purpose of conducting

the products of combustion from the manifold to the heating space 13.

A pair of nipples 17, 18 project radially from the diametrically opposite side walls 12 near the bottom of the jacket and are preferably provided with flange couplings 19, 19' on their outer ends for union with the oppositely extending conductor pipes 20, 21. The nipples are in open communication with the bottom of heating space 13 and the respective conductor pipes 20, 21. The conductor pipe 21 connected with the forwardly projecting nipple 17 is the upper branch of a substantially Y-shaped section of pipe designated generally at 22, the stem 22' of which is joined with the exhaust pipe 6', whereas the adjacent branch will be hereinafter referred to.

The conductor pipe 20 connected to the rearwardly projecting nipple 18 is substantially L-shaped and extends rearwardly and downwardly. The lower end of pipe 20 is adapted for connection with an opening 23 in the side wall near the rear end of a closed cylindrical heating casing 24. The casing is mounted longitudinally on a liquid fuel conducting line 25 which extends through the interior of the casing concentric therewith. Near the forward end of said casing on the side wall opposite the opening 23 is a similar opening 26 which communicates with another L-shaped conductor pipe 27. The conductor pipe is coupled to the wall of the casing surrounding said opening and extends upwardly and forwardly and is coupled to the branch 28 adjacent branch 21 of the Y-shaped pipe 22.

The products of combustion pass out of the exhaust manifold into the top of the heating space 13 and are dispersed therefrom in opposite directions as indicated by the arrows on the drawings. The incoming mixed charge from casting 10 is heated by the jacket 11 as it passes through pipe 8 on its way to the engine cylinder. Part of the gases pass out of the bottom of the jacket rearwardly through conductor pipe 20, through the heating casing 24 and return to the exhaust pipe 6' by way of conductor pipe 27, branch 28 and stem 22'. In the casing 24 the liquid fuel in pipe line 25 is converted into a gas or vapor by the heat of the products of combustion circulating through said casing. The remaining portion of the products of combustion may flow directly from the jacket 11 into the exhaust pipe 6' through the branch 21 and the stem 22' of the Y-shaped pipe 22. It will be noted that any back pressure in the rearward flow of the products of combustion will be equalized by the siphon effect produced by reason of the increased flow through the upper branch of the Y-shaped pipe 22. Increased flow through branch 21 creates a suction in branch 28 until the pressures are balanced.

The liquid fuel flows by gravity from the supply pipe 7 into the auxiliary reservoir 29 and the level of the liquid therein is controlled by a float 29' which coacts with a valve not shown in the drawings. From the bottom of the reservoir the fuel is conducted into a passage 30 formed integral with a supporting member 31. The passage 30 communicates with an enlarged portion 25' of the fuel conducting pipe line 25. The enlarged portion 25' projects at right angles to the pipe line 25 and functions as a stand pipe. The suction stroke of the engine draws the liquid fuel out of the stand pipe 25' and the amount withdrawn is controlled by regulating needle valve 32 with respect to the valve seat 33 therefor by adjusting the handle 34. The needle valve is supported on the member 31 having the stem thereof projecting axially into the stand pipe 25' and abutting the valve seat 33 which extends across the inner walls of the stand pipe 25' above the fluid level in the reservoir 29.

From the stand pipe 25' the liquid fuel is drawn into pipe line 25 by the suction stroke of the engine where it is converted into a gas or vapor when it passes through the heating casing 24 mounted on the pipe line 25. The pipe line 25 as illustrated is formed with a pair of extensions forward of the casing 24, one indicated at 35 and the other at 35'. The extension 35 is of angle shape and is provided therein with a valve seat 36 and an adjustable valve 37 coacting with seat 36. Coupled to the extension 35 is a nozzle 36' which extends through the outer wall of the casting 10 for purposes to be referred to. The extension 35' is of a length to extend around the casting 10 and project through the forward wall thereof. The extension 35' is formed with a nozzle to be hereinafter referred to.

The casting 10 is substantially a right angled shell having flanges 38, 39 on its perpendicular portion by which it is joined at its bottom to the support 31 and at its top with the flange 9' of the section of supply pipe 8 by suitable holdfast devices. The perpendicular portion of the casting 10 provides on its interior a mixing compartment 40 at its upper end, a trap 41 at its lower end partitioned from each other in a manner hereinafter to be referred to. The trap 41 is provided at the lower extremity of the perpendicular portion to collect the condensed liquid fuel which is conducted away through an opening 42 in the side walls thereof.

Communicating with the interior of the perpendicular portion of the casting 10 and extending forwardly at right angles from its outer wall is an air supply pipe 43 having an open forward end. The air conducted through pipe 43 into the chamber of the perpendicular portion is controlled by the pivoted butterfly choke valve 44 which is operated by a rod 45 from any desired point.

The interior partition walls in the perpendicular portion of the casting 10 consists of a flat flutter valve 46 of greater area than a semicircle. The corded edge of the valve is pivoted at 47, 48 to the outer wall of the perpendicular portion while its curved edge abuts against the inner wall thereof with the face of the valve inclined at an angle, as will be understood by referring to Figure 1 of the drawing. Another partition wall 49 segmental in shape is fixed to the walls of the perpendicular portion and extends radially to the pivoted edge of the flutter valve 46, whereby the remaining internal area of the perpendicular portion is partitioned. The partition formed by the flutter valve 46 and the segmental wall 49 divide the mixing chamber 40 from the trap 41 and the mouth of the air pipe 43.

The segmental wall 49 is provided with an upwardly flared opening or nozzle 50 extending therethrough which is located in alignment with nozzle 36' of the gaseous fuel supply pipe extension 35 which enters the side wall of the perpendicular portion of casting 10 just above the segmental wall. Air comes into the chamber from the pipe 43 and up through the flared opening 50 where it mixes with the incoming gaseous or vaporized fuel from the nozzle 36' in the mixing compartment 40.

The flutter valve 46 is provided on its curved edge with a cavity 51 through which projects the nozzle 52 on the end of the gaseous fuel pipe extension 35'. The cavity allows the flutter of the valve 46 without binding on the nozzle. A pair of ears 53 on the face of the valve 46 are rigidly connected by means of the links 54 to a spring controlled bolt 55, the tension upon which may be varied by turning the knob 56. The vacuum caused by the intake of the engine tends to swing the flutter valve 46 open and allow air from pipe 43 to displace the vacuum in the mixing compartment 40. The amount of air permitted to rush into the mixing compartment 40 depends upon how far the valve 46 may swing open, and its swing can be regulated by the tension placed on the spring compressed bolt 55 adjusted by knob 56.

Below the jacket 11 and extending across the section of pipe 8 above the mixing compartment 40 is a pivoted butterfly throttle valve 57 which regulates the amount of mixed gases which are allowed to be drawn into the intake manifold 5. The valve is controlled by a rod 58 which extends to the desired control point.

In operation, the air rushing through the flared opening 50 draws the vaporized fuel from the pipe line 25, through the extension 35 and nozzle 36' into the mixing compartment 40. As the fuel leaves the nozzle 36', it is mixed with the air rushing through the

opening 50 and the richness of such mixture may be varied as desired by adjusting the valve 37 with respect to the valve seat 36. The richness of the mixture may be further varied by manipulation of the needle valve 32 with respect to the valve seat 33, whereby the flow of liquid into the pipe line 25 may be controlled to vary the density of the vaporized fuel within the pipe line 25.

As the speed of the engine increases, the flutter valve 46 is forced open whereby additional air is admitted to the compartment 40 from the pipe 43. As the air from the pipe 43 rushes past the nozzle 52, additional fuel is drawn from the pipe line 25, through the extension 35' and nozzle 52 into the mixing compartment 40, thereby tending to equalize the richness of the mixture within the compartment 40 at varying speeds of the engine. To additionally increase the efficiency of the engine, the mixture is passed from the compartment 40 through the heating jacket 11 before being discharged into the cylinders.

It is thought that the many advantages of a charge forming device in accordance with this invention will be readily apparent, and although the preferred embodiment is as illustrated and described, yet it is to be understood that changes in the details of construction may be made, which fall within the scope of the invention as defined in the appended claim.

What I claim is:—

A charge forming device comprising, a liquid fuel conducting line, a heater for vaporizing the fuel on its travel through the line, means to provide a mixing chamber for receiving the vaporized fuel, a conduit leading from said line to the mixing chamber, means for admitting air to the mixing chamber in proximity to the mouth of said conduit to be mixed with the vaporized fuel discharged from said conduit, an intake manifold in communication with said chamber, a jacket encircling a portion of said intake manifold, an exhaust manifold in communication with said jacket for discharging products of combustion therein, a pipe leading from said jacket to said heater, a return pipe leading from said heater to the exhaust manifold, and a suction pipe leading from said jacket and opening into said return pipe at an acute angle thereto and in proximity to the exhaust manifold to prevent back pressure in said return pipe.

In testimony whereof, I affix my signature hereto.

WILLIAM B. ELLIS.
